REFRIGERATING APPARATUS

Leslie B. M. Buchanan, Springfield, Mass., assignor to Westinghouse Electric & Manufacturing Company, East Pittsburgh, Pa., a corporation of Pennsylvania

Application October 31, 1936, Serial No. 108,516

11 Claims.

(Cl. 62—4)

My invention relates to apparatus for refrigerating different zones of a refrigerator to predetermined temperatures, and it has for an object to provide improved apparatus of this kind.

5 A further object of my invention is to provide improved two-temperature refrigerating apparatus which will be reliable in operation and inexpensive to produce.

10 A still further object of the invention is to provide improved means for varying the effective cooling area of an evaporator by controlling the operation of a single valve from different portions of the evaporator.

15 A still further object of my invention is to provide improved means for selectively effecting refrigeration of different zones of a refrigerator.

20 These and other objects are effected by my invention as will be apparent from the following description and claims, taken in connection with the accompanying drawing forming a part of this application, in which:

Fig. 1 is a diagrammatic view of a two temperature refrigerating machine constructed in accordance with my invention; and,

25 Fig. 2 is a sectional view, somewhat diagrammatic, of an expansion valve employed in the apparatus shown in Fig. 1.

Reference will now be had to the drawing wherein I disclose a refrigerator cabinet structure 10 having relatively low and high temperature chambers 11 and 12 formed therein and cooled by respective evaporator elements 13 and 14. Refrigerant is circulated through the evaporators 13 and 14 by a condensing unit, generally indicated at 15, and including a compressor 16, a motor 17 for driving the compressor, and a condenser 18, the latter being cooled in any suitable manner, such as, for example, by a fan 19. A liquid refrigerant reservoir, shown at 21, may be connected to the condenser 18 for storing refrigerant condensed thereby.

Condensed refrigerant is conveyed to the evaporators 13 and 14 from the reservoir 21 by means of a conduit 22. Refrigerant vaporized in the evaporators 13 and 14 passes to the compressor 16 through a conduit 23. A device 24, preferably a thermostatic expansion valve, is arranged in the liquid supply conduit 22 for controlling the flow of condensed refrigerant to the evaporators 13 and 14 and for reducing the pressure of the refrigerant. The valve 24 will be referred to more in detail hereinafter. The refrigerating apparatus described in the foregoing 55 is of the compressor-condenser-expander type.

Liquid refrigerant, passed by the valve 24, enters a header 25 provided in the upper portion of the evaporator 13. A conduit 26 provides communication between the header 25 and an inlet header 27 formed in the evaporator 14. 5 The suction conduit 23 connects with an outlet header 28 formed in the evaporator 14. As shown, the evaporator 13 may include shelf portions 29 for supporting trays 31 for fluid to be congealed. The evaporator 13 operates, therefore, to congeal liquid and to reduce the temperature of the air in the chamber 11 to a relatively low value. The evaporator 14 may be provided with fins 32 as shown, and cools the air in the chamber 12 to a value somewhat higher than 15 the temperature of the air in the chamber 11.

From the foregoing, it will be apparent that refrigerant delivered to the header 25 will fill the evaporator 13 before flowing through the conduit 26 to the evaporator 14. The evaporator 13, therefore, receives refrigerant in preference to the evaporator 14.

In accordance with my invention, condensed refrigerant is confined to the evaporator 13 when cooling of the chamber 11 is effected and, when 25 the chamber 12 is being cooled, liquid refrigerant substantially fills both evaporators 13 and 14. The means for obtaining this operation will now be described.

While other suitable forms of devices 24 may 30 be employed, I prefer to employ an expansion valve including a valve structure which is actuated in response to the superheat of the vaporized refrigerant. Such an expansion valve is shown in Fig. 2 and includes a casing 33 having a valve 35 seat 34 formed therein. A valve member 35 cooperates with the valve seat and is actuated by a diaphragm member 36. The casing 33 is divided into two chambers 37 and 38 which communicate, respectively, with the liquid supply 40 conduit 22 and with the evaporator header 25.

The valve casing 33 defines a chamber 39 above the diaphragm 36 which is in communication with a conduit 41 having first and second bulbs or reservoirs 42 and 43 connected therein. A 45 suitable volatile fluid, preferably, the same as the fluid employed as a refrigerant in the system, is contained within the bulbs 42 and 43, conduit 41, and the chamber 39. The bulbs 42 and 43 are disposed in heat transfer relation with the respective conduits 26 and 23, adjacent to their points of connection with the evaporators 13 and 14.

The diaphragm is subjected upon its top side to the pressure of the fluid in the chamber 39, 55

which pressure is a function of the temperature of the liquid in the bulb 42 or 43. The pressure which is effective is that corresponding to the temperature of the lower temperature bulb.

- 5 This condition prevails at all times due to the fact that a volatile fluid is employed, and, therefore, a higher temperature at the warmer bulb will not raise the pressure in the chamber 39 and conduit 41 as the fluid vaporized by the higher 10 temperature is immediately condensed in the lower temperature bulb. Accordingly, the pressure is determined by the lowest temperature to which the fluid is subjected. The bulb 42 is, preferably, disposed in the low temperature 15 chamber 11 and in contact with the evaporator discharge conduit 26 so that it operates at lower temperature than the bulb 43, except during certain periods as described hereinafter.

The underside of the diaphragm 36 is subjected to the pressure of refrigerant in the evaporator 13 or 14, which pressure prevails in the chamber 38 of the valve 24. A biasing means, such as a spring 44, biases the diaphragm 36 and valve 35 upwardly and may determine the value 25 of the superheat to which the valve responds. Preferably, the spring 44 is adjustable by any well known means (not shown) whereby the value of the superheat maintained may be varied.

During operation with the bulb 42 at a lower 30 temperature than bulb 43, only the evaporator 13 receives condensed refrigerant, because the valve 24 responds to the superheat of the refrigerant in conduit 26 and controls the supply of 35 condensed refrigerant to maintain a predetermined amount of superheat, for example, 10°, in the gas passing from the evaporator 13 to the evaporator 14 through the conduit 26. At this time some slight cooling of the evaporator 14 may be effected as the gas passing therethrough 40 to the suction conduit 23 abstracts some heat from the evaporator 14 as the gas is further superheated. The refrigerant charge in the system is such that a substantial amount of liquid refrigerant is present in the reservoir 21 during 45 the periods when evaporation is effected in the evaporator 13 alone.

In accordance with my invention, refrigeration of the chamber 12 is effected by transferring the point at which superheat is controlled to the 50 conduit 23. Accordingly, the bulb 43 is rendered effective to determine the pressure in the chamber 39 of the valve 24. This may be effected by heating the bulb 42 to a temperature slightly in excess of the temperature of the bulb 43. Preferably, an electrical heater 45 is disposed in heat transfer relation with the bulb 42 for this purpose.

As the temperature of the fluid in the bulb 42 is heated by the heater 45, the pressure in the 55 chamber 39 rises. Accordingly, the valve 35 is moved away from its seat 34 and refrigerant flows from the reservoir 21 through the valve 24 to the header 25 and overflows into conduit 26 and substantially fills the evaporator 14. The 60 superheat present in the gas is under control of the bulb 43 and the valve 24 operates to maintain the gas passing through the conduit 23 in a superheated condition.

As the evaporator 14 operates at pressure and 65 temperature values higher than the values at which vaporization is effected in the evaporator 13, vaporization of refrigerant in the evaporator 13 substantially ceases, during refrigeration of the evaporator 14. It will be understood that 70 the evaporator 13 is filled with liquid refrigerant

which provides a seal for preventing gas generated in the expansion valve 24 or in the evaporator 14 from entering and condensing in the low temperature evaporator 13, which action would add heat to the latter.

Operation of the condensing unit 15 and the heater 42 is preferably automatically controlled in accordance with temperature conditions within the chambers 11 and 12. As shown in Fig. 1, a thermostat 46 of the gas type controls operation of the condensing unit 15 in accordance with the temperature of the evaporator 13 and a thermostat 47, shown by way of example as a bimetal strip, controls the condensing unit 15 and the heater 45 in accordance with the temperature of the air in the chamber 12.

The thermostat 46 preferably includes a bellows 48 connected by a tube 49 to the bulb 51, the latter being disposed in heat transfer relation with the evaporator 13. As is well understood, 20 a volatile fluid is contained in the bulb 51, tube 49 and bellows 48 whereby the latter expands and contracts as the temperature of the evaporator 13 and bulb 51 increases and decreases. The bellows 48 actuates a switch 52 in such 25 manner that it is closed and opened in response to predetermined high and low temperatures of the evaporator 13. The thermostat 46 is shown, for the sake of clearness, in its simplest form and it is to be understood that certain refinements, 30 such as, for example, snap-acting switch mechanisms have been omitted.

The source of power for the compressor motor 17 and the heater 45 is represented by line conductors L₁ and L₂. The switch 52 is connected 35 in series in a circuit including line conductor L₁, the motor 17, a conductor 53, the switch 52 and line conductor L₂. As the temperature of the evaporator 13 increases to a predetermined value, the switch 52 is closed by the expanded 40 bellows 48 and initiates operation of the motor 17 and, conversely, as the temperature of the evaporator 13 decreases to a predetermined value, the switch 52 is opened by the bellows 48 and terminates operation of the motor 17.

The thermostat 47 includes a movable bimetallic member 54 which engages stationary contacts 55 and 56 as the temperature of the air in the chamber 12 increases to a predetermined value and which is disengaged from said contacts 55 and 56 when the temperature of the air decreases to a predetermined value. The movable member 54 is connected to the line conductor L₂ and the contact 55 is connected to the conductor 53 for controlling energization of the motor 17. The contact 56 is connected to one terminal of the heater 45; the other terminal of which is connected to line conductor L₁. Accordingly, engagement of the movable member 54 with contacts 55 and 56 in response to a predetermined temperature within the chamber 12 effects energization of the compressor motor 17 and the heater 45.

Operation

As shown in the drawing, the temperatures prevailing within the chambers 11 and 12 are below the values at which their respective thermostats 46 and 47 operate to effect operation of the condensing unit 15. Assume that the temperature of 70 the evaporator 13 increases to the value at which the thermostat 46 closes. The motor 17 is energized and the condensing unit 15 operates to supply refrigerant to the evaporator 13. As the heater is deenergized, the bulb 42 is at a lower 75

temperature than the bulb 43 and, as described heretofore, the device 24 is controlled to maintain the proper superheat in the refrigerant vaporized in the evaporator 13. Accordingly, only 5 gaseous refrigerant circulates through the evaporator 14, the cooling effect of which is slight. As the temperature of the evaporator 13 is depressed to the desired value, the thermostat 46 operates to terminate operation of the condensing unit 15.

Assume a rise in temperature of the air in the chamber 12, the thermostat 47 operates to engage the movable member 54 with contacts 55 and 56, whereby the condensing unit 15 is operated and 15 the heater 45 is energized. Therefore, the bulb 43 operates at a lower temperature than the heated bulb 42 and, as described heretofore, the superheat of the vaporized refrigerant is controlled by the device 24 and bulb 43. During this operation, the device 24 admits sufficient refrigerant 20 to fill a substantial portion of the evaporator 14.

Refrigerant is vaporized in the evaporator 14 for cooling the air in the chamber 12, the pressure of the vaporized refrigerant being at a high- 25 value than when the evaporator 13 is cooled. The evaporator 13 and conduit 26 are filled with liquid refrigerant at this time, whereby a seal is defined for preventing refrigerant vaporized in the evaporator 14 from condensing in the evaporator 13. Accordingly, undesirable heating of 30 the evaporator 13 is prevented.

As the thermostat 47 moves to its open position in response to a predetermined low temperature of the air in the chamber 12, the condensing unit 35 15 is stopped and the heater 45 is deenergized. In the event that both thermostats 46 and 47 close in response to cooling demands by the chambers 11 and 12, the evaporator 14 in chamber 12 is given preference due to the fact that 40 heater 45 is energized under this condition, and therefore the superheat of the vaporized refrigerant is controlled by bulb 43. It will be understood that the evaporator 13 may be given preference over the evaporator 14 when both require cooling in accordance with my invention.

From the foregoing it will be apparent that the device 24 functions as a thermostatic expansion valve with means for controlling the superheat of the vaporized refrigerant at a plurality 50 of selected locations along the evaporator structure. Accordingly, the effective area of an evaporator, or the portion thereof in which vaporization is effected, may be controlled in accordance with my invention. In this connection it will be understood that the invention is not limited to two temperature refrigerators but may be applied to single evaporators to control the effective cooling area thereof.

It will be understood that other forms of refrigerant condensing units and control elements 60 may be employed in my improved refrigerating system without departing from the spirit of the invention.

While I have shown my invention in but one 65 form, it will be obvious to those skilled in the art that it is not so limited, but is susceptible of various changes and modifications without departing from the spirit thereof, and I desire, therefore, that only such limitations shall be 70 placed thereupon as are imposed by the prior art or as are specifically set forth in the appended claims.

What I claim is:

1. In apparatus for refrigerating first and second zones, the combination of first and second

evaporators disposed for cooling said zones, respectively, means for supplying refrigerant to the evaporators, a device common to both evaporators for selectively controlling the vaporization of refrigerant therein, first and second temperature responsive elements associated with the respective evaporators for controlling said device, and means for controlling the operation of the refrigerant supply means and for selecting the element which is to control the device. 10

2. In apparatus for refrigerating first and second zones, the combination of first and second evaporators disposed for cooling said zones, respectively, means for supplying refrigerant to the evaporators, a device common to both evaporators for controlling the admission of refrigerant thereto, first and second temperature responsive elements associated with the respective evaporators for controlling said device, and means for controlling the operation of the refrigerant supply means and for selecting the element which is to control the device. 15

3. In apparatus for refrigerating first and second zones, the combination of first and second evaporators disposed for cooling said zones, respectively, means for supplying refrigerant to the evaporators, a device common to both evaporators for selectively controlling the vaporization of refrigerant therein, first and second temperature responsive elements associated with the respective evaporators for controlling said device, and means responsive to temperatures within the respective zones for selecting the element which is to control the device. 25

4. In refrigerating apparatus, the combination 35 of first and second evaporating elements, means for supplying condensed refrigerant to said elements in such manner that it flows into the first element in preference to the second element, a device for regulating the flow of refrigerant to the elements, first and second means responsive respectively to the temperature of the refrigerant in the evaporating elements for controlling said device, and means for selectively rendering the first or second temperature responsive means 40 45 operative to control the device.

5. In refrigerating apparatus, the combination of first and second evaporators, means for condensing refrigerant for the evaporators, means for conveying the condensed refrigerant to the first evaporator, a conduit for conveying refrigerant from the first evaporator to the second evaporator, a second conduit for conveying refrigerant vaporized in the evaporators from the second evaporator to the refrigerant condensing means, first and second means responsive to the temperature of the refrigerant flowing through said first and second conduits respectively for controlling the flow of condensed refrigerant to the evaporators and means for selecting the temperature responsive means which is to control 50 55 the flow of condensed refrigerant. 60

6. In refrigerating apparatus, the combination of first and second evaporators, means for condensing refrigerant for the evaporators, means for conveying the condensed refrigerant to the first evaporator, a conduit for conveying refrigerant from the first evaporator to the second evaporator, a second conduit for conveying refrigerant vaporized in the evaporators from the second evaporator to the refrigerant condensing means, a valve for controlling the flow of condensed refrigerant conveyed by said refrigerant conveying means, means responsive to the pressure of the refrigerant in the evaporators for 70 75 80 85 90 95

- actuating said valve in one direction, temperature responsive means for actuating the valve in another direction in opposition to the pressure responsive means, and means for selectively rendering the temperature responsive means responsive to the temperature of the refrigerant discharged from the first evaporator or to the temperature of the refrigerant discharged from the second evaporator.
10. In refrigerating apparatus, the combination of means defining first and second chambers to be refrigerated, first and second evaporators disposed for cooling the chambers, respectively, a common means for supplying condensed refrigerant to the evaporators in such manner that it flows into the first evaporator until filled and thence into the second evaporator, means for withdrawing the refrigerant vaporized in the evaporators from the second evaporator, a first means responsive to the superheat of the refrigerant vaporized in the first evaporator for controlling the flow of condensed refrigerant to the evaporators, a second means responsive to the superheat of the refrigerant withdrawn from the second evaporator for controlling the flow of condensed refrigerant to the evaporators, means responsive to predetermined temperatures within the first and second chambers for respectively effecting operation of the refrigerant supply means, said second superheat responsive means being rendered effective to control the flow of refrigerant during periods when the second temperature responsive means effects operation of the refrigerant supply means, and said first superheat responsive means being effective at other times that the refrigerant supply means is operated.
8. In refrigerating apparatus, the combination of first and second evaporators, means for condensing refrigerant for the evaporators, means for conveying the condensed refrigerant to the first evaporator, a conduit for conveying refrigerant from the first evaporator to the second evaporator, a second conduit for conveying refrigerant vaporized in the evaporators from the second evaporator to the refrigerant condensing means, a valve for controlling the flow of condensed refrigerant conveyed by said refrigerant conveying means, means responsive to the pressure of the refrigerant in the evaporators for actuating said valve in one direction, a gas-type thermostat element for biasing the valve in opposition to said pressure responsive means, said thermostat element including an enclosed gas and liquid space having first and second liquid reservoir portions disposed in heat exchanging relation with the first and second conduits respectively, means for heating the first reservoir portion, means for effecting operation of the refrigerant condensing means and for energizing the heater during periods when the second evaporator is rendered active, and means for effecting operation of the refrigerant condensing means without energizing the heater when the first evaporator is rendered active.
9. In refrigerating apparatus, the combination of first and second evaporators, means for condensing refrigerant for the evaporators, means for conveying the condensed refrigerant to the first evaporator, a conduit for conveying refrigerant from the first evaporator to the second evaporator, a second conduit for conveying refrigerant vaporized in the evaporators from the second evaporator to the refrigerant condensing means, a valve for controlling the flow of condensed refrigerant conveyed by said refrigerant conveying means, means responsive to the pressure of the refrigerant in the evaporators for actuating said valve in one direction, a gas-type thermostat element for biasing the valve in opposition to said pressure responsive means, said thermostat element including an enclosed gas and liquid space having first and second liquid reservoir portions disposed in heat exchanging relation with the first and second conduits respectively, means for heating the first reservoir portion, means for effecting operation of the refrigerant condensing means and for energizing the heater during periods when the second evaporator is rendered active, and means for effecting operation of the refrigerant condensing means without energizing the heater when the first evaporator is rendered active.
10. In a refrigerating system, the combination of an evaporator, circulating means for withdrawing vaporous refrigerant from the discharge end of the evaporator and for translating condensed refrigerant to the admission end thereof, a valve for controlling the admission of condensed refrigerant to the evaporator, a pressure responsive element for actuating the valve and subjected to the pressure of the refrigerant in the evaporator, means defining a chamber for a volatile fluid and so disposed that said pressure responsive element is biased by the pressure of said fluid in opposition to the pressure of the refrigerant, said chamber including first and second reservoir portions for condensed fluid, said second reservoir portion being disposed in heat exchanging relation with the discharge end of the evaporator from which vapor is withdrawn, said first reservoir portion being disposed in heat exchanging relation with a portion of the evaporator intermediate the admission and discharge ends thereof, a heater for the first reservoir portion, means for effecting operation of the heater and the circulating means whereby vaporization of refrigerant is effected throughout a substantial portion of the evaporator and said pressure responsive element is subjected to the pressure of the volatile fluid corresponding to the temperature of said second reservoir portion, and means for effecting operation of the circulating means whereby vaporization of refrigerant is effected in the portion of the evaporator between the admission end thereof and said intermediate portion and the pressure of the volatile fluid on the pressure responsive element corresponds to the temperature of the first reservoir portion.
11. In a refrigerating system, the combination of an evaporator having a plurality of portions thereof serially arranged with respect to the flow of refrigerant, refrigerant circulating means for withdrawing vaporous refrigerant from the evaporator and for delivering condensed refrigerant thereto, a device for controlling the admission of condensed refrigerant to the evaporator, a plurality of means responsive to the superheat of the vaporous refrigerant in the respective evaporator portions for controlling said device and means for selectively rendering the superheat responsive means active to control the device so that the area of the evaporator which is effective for cooling is varied.
